QUADRANTAL ERROR CORRECTOR SYSTEM

William P. Lear, Dayton, Ohio, assignor, by
mesne assignments, to Lear Avia, Inc., Piqua,
Ohio, a corporation of Illinois

Application October 17, 1940, Serial No. 361,544

9 Claims. (Cl. 250—11)

The present invention relates to quadrantal error compensating mechanisms which effect bearing corrections for radio direction indicators, and more particularly to novel multiple arrangements for selective compensation in a plurality of ranges of radio frequency reception.

To obtain accurate azimuthal bearing indications, radio direction finder systems are generally provided with a so-called quadrantal error compensator to mechanically correct deviation errors of the indicator readings, over 360° of arc. The errors are due to directional distortions of the received radio waves, inherent in the radio installation. The bearing deviations usually are of the order of a few degrees, and in some instances may reach to 10° or even 20°, depending upon the character and closeness of the surrounding metallic objects.

It has been found that the quadrantal errors depend upon the frequency range of radio reception. Thus, when operating on radio frequencies in widely separated reception bands, the corrections were not fully reliable unless the corrector mechanism was correspondingly rearranged or changed in the different ranges. The present invention permits such change to be effected with a minimum of time and attention. This is particularly advantageous aboard an airplane. Quadrantal errors have been found to depend upon the degree of draught of a ship in water. The invention is accordingly also applicable aboard ship for readily accommodating the radio directional error corrections to the degree of draught.

It is the principal object of the present invention to provide quadrantal error corrector arrangements incorporating a plurality of corrector cams calibrated for correspondingly different reception bands, selectively placed into operation by the mere twist of a knob or flip of a lever. The corrector cams are arranged adjacent each other. The associated mechanism selectively engages one cam at a time. The number of cams used depends on the frequency range or bands over which the system is to operate, and may well correspond to one-half or the full number of frequency reception bands of the direction finder receiver. Each cam is individually calibrated to properly quadrantly compensate for the radio bearing indications in the associated band.

Further objects, advantages and capabilities of the invention will become apparent in the following description of specific embodiments thereof illustrated in the accompanying drawings, in which:

Fig. 1 is a schematic diagram of an automatic radio direction finder system incorporating the invention.

Fig. 2 is an enlarged perspective view showing of a quadrantal error compensator section.

Fig. 3 is a plan view of a calibrated corrector cam.

5 Fig. 4 is a plan view of one embodiment of the multiple quadrantal error corrector mechanism of the invention.

Fig. 5 is a vertical cross-sectional view of the mechanism of Fig. 4, taken along the line 5—5 10 thereof.

Fig. 6 is a plan view of a modified form of the invention.

Fig. 7 is a vertical cross-sectional view taken along the line 7—7 through the mechanism of 15 Fig. 6.

Fig. 8 is a plan view of a further embodiment of the present invention.

Fig. 9 is a vertical cross-sectional view through the mechanism of Fig. 8, taken along the line 20 9—9 thereof.

Fig. 10 is an enlarged cross-sectional view taken along the line 10—10 of Fig. 4, showing details of the cam selector thereof.

Figs. 11, 12 and 13 illustrate details of the cam 25 selector of Fig. 10.

Figs. 14, 15 and 16 show details of the cam selector of the embodiment illustrated in Fig. 7.

Figs. 17, 18 and 19 illustrate details of the cam selector mechanism of the embodiment of the 30 invention shown in Figs. 8 and 9.

An automatic radio direction finder system embodying the quadrantal error corrector mechanism of the invention is diagrammatically illustrated in Fig. 1. The radio receiver and electronic control section of the system is indicated at 20, and may well embody the system disclosed in my copending application Serial No. 286,733, filed on July 27, 1939, now Patent No. 2,308,521, issued January 19, 1943, and assigned to the same 35 assignee as the present invention.

A non-directional antenna 21, and a rotatable directional or loop antenna 22 shown in dotted lines within streamline housing 23, are connected to the radio frequency input of direction finder 20 through lead 21' and loop cable 24 respectively. Ear phones 25 are for the aural determination of the station tuned-in, or for effecting aural-null directional determinations.

An electric motor, controlled through cable 26 50 by direction finder circuits 20, is arranged within housing 27 for directly rotating loop antenna 22 in a manner such as disclosed in the copending application referred to, and as will be described in more detail hereinafter. A 360° azimuthal indicator 28 is mechanically connected to loop antenna 22 by a flexible mechanical shaft 29 for indicating the bearing positions of the loop antenna at a remote location therefrom, such as 55 near the pilot. As will be later shown, the quadrantal error corrector mechanism enclosed within

60

housing 27 is mechanically connected between rotatable loop antenna 22 and indicator 28, whereby the indications by indicator needle 30 on the dial of indicator 28 are automatically corrected to correspond to the true geometrical bearing on the radio station tuned-in.

The streamline housing 23 is used where the loop antenna is mounted exterior of the body of the aircraft indicated at 31. The quadrantal error corrector mechanism within housing 27 is, in the illustrated embodiment, mounted adjacent the loop antenna and against the inner surface of the aircraft body 31. The position of the quadrantal error corrector mechanism may, however, be remote from the loop antenna. Also, the loop motor may be positioned apart from the quadrantal error corrector mechanism, such as actually within the chassis of the direction finder receiver. A hinged cover 32 on quadrantal error corrector housing 27 may be opened by means of locking nut 33, to permit access to the corrector mechanism within. Selective changes in the quadrantal error corrector may thus be directly effected. If the loop antenna is in a relatively inaccessible place, the corrector mechanism enclosed in housing 27 is preferably separate from the loop antenna, being placed nearer the operator who may readily effect the selective operation.

Reference is now made to Fig. 2, the perspective illustration of an operating section of the quadrantal error corrector mechanism. The arrangement illustrated corresponds to the basic corrector assembly incorporated in the quadrantal error corrector of my copending application, Serial No. 344,854, filed on July 11, 1940, for "Quadrantal compensators," and assigned to the same assignee as the present case. It is to be understood, however, that the present invention may be practiced with other equivalent quadrantal error correcting arrangements, insofar as the corrections, *per se*, are effected; the invention being more broadly concerned with the multiple arrangements and selective control of the compensator. Once a selection is made, the mechanism operates in the usual manner to compensate through calibrated action, as by a cam.

Shaft 35 is connected directly to the loop antenna, and is connected to central shaft 36 of the mechanism through flexible coupling member 37. The indicator 28 is mechanically connected to the mechanism by flexible cable 29 through horizontally mounted shaft 38. A worm 40 is secured to shaft 38 and meshes with worm gear 41. The mechanical engagement between loop shaft 35 and indicator shaft 38 is arranged to be rigid yet relatively angularly displaceable under the control of a cam. A trolley 42, comprised of linked arms 43, 44, 45 and 46 is incorporated in the illustrated corrector mechanism.

The trolley arms are respectively linked at pivotal points 47, 48 and 49. The free end of arm 43 is adjustably secured to the upper end of vertical shaft 36; the free end of link 46, being secured adjacent thereto to the upper end of a sleeve 50 concentric about vertical shaft 36. Thumb screws 51 and 52 are used to respectively grip the arms 43 and 46 to the shaft and sleeve ends. The worm gear 41 is mechanically secured to sleeve 50 by suitable set screws indicated at 53, 53. A spring 54 is arranged between links 44 and 46 to mechanically bias the pivotal point 48 between links 44 and 45 radially outwardly.

Rotation of shaft 38 in either direction causes a corresponding angular displacement of the

trolley 42 and loop shaft 35. A cam follower 55 is secured at the pivotal region 48 in the form of an upwardly extending rod having a plurality of cam contact lugs or nibs 56 projecting in different directions. Internally cammed members 57, 58 are spaced apart for individual engagement with one of the lugs 56. The internal cam surface 64 of cam 57 is engaged with its associated cam follower lug 56, to define the degree of radial extension of the trolley.

Variation in the radial disposition of internal cam surface 64 determines the amount of angular displacement effective between shaft 36 and sleeve 50. The radial cam variation correspondingly controls the angular difference between the actual positions of the loop antenna as connected to shaft 35, and the bearing indication of indicator 28. By suitable design of the corrector cam, the proper compensation of the readings of indicator 28 may be effected throughout the 360° range in accordance with the determined quadrantal bearing errors of the installation for the radio frequency range corresponding to cam 57. To effect quadrantal error compensation for another frequency reception band, another cam surface such as 62 of cam 58 is engaged with its associated cam follower nib 56 through the suitable actuation of member 55. The selective cam control action will be described in more detail hereinafter. As many individual corrector cams may be used as is necessitated by the overall radio reception range of the system, and design refinement.

A typical calibrated corrector cam is illustrated in plan view in Fig. 3. The cam blank 63 has an inscribed 360° graph designed to translate quadrantal error determinations for the respective band into the correction curve, in a direct, accurate and simple manner. A series of concentric circles 64 correspond to the magnitude of the quadrantal error in degrees. Centrally disposed circle 65 corresponds to zero quadrantal error correction. The concentric circles radially larger than zero circle 65 refer to a negative quadrantal error correction; the smaller ones, to a positive correction. Arcuate radial lines 66 are arranged at 10° separations over 360° of arc, being designed in accordance with the geometrical law of motion and coaction of the cam followers with respect to the internal cammed surface. Internal cammed surface 67 of cam blank 63 is the result of a smooth continuous curve connecting the determined compensation errors plotted on blank 63. Complete and accurate quadrantal error compensation over the 360° azimuth is effected by the mechanism of the invention, being automatically and continuously present for all indications.

The embodiment of the invention illustrated in Figs. 4 and 5 comprises four spaced cams 57, 58, 59 and 60, individually calibrated in accordance with the quadrantal errors of the associated frequency reception bands as previously set forth. Cam follower member 55 contains four longitudinally spaced cam follower nibs 56 which are radially arranged at 90° separations. Only one nib 56 at a time may contact its associated cam surface. The loop motor is positioned within the quadrantal housing 27, as indicated at 70 in dotted lines. An electromagnetic clutch 71 couples motor 70 to pinion 72. Pinion 72 engages gear 73 which is fastened to horizontal rod 38 of the corrector mechanism. Flexible shaft 29 connected to indicator 28 is fastened to the end of rod 38 by coupling piece 74. Motivation of

the loop antenna occurs by suitable energization of motor 70 and electromagnetic clutch 71 in response to radio wave reception, as described in detail in the said Patent No. 2,308,521. The loop antenna drive occurs through gearing 72, 73, and 49, 41 of the quadrantal error corrector mechanism. Indicator 28 coupled to cable 29 follows the angular orientation of the loop antenna with proper compensation through the corrector mechanism.

The individual corrector cams 57, 58, 59 and 60 are spacedly mounted by suitable posts 75 bolted on sub-panel 76. Washers 77 predeterminedly space the cams from each other. Six spaced bolts 78 are arranged about the periphery of the cams, holding respective posts 75 and washers 77 together. Spring 54 mechanically biases the cam follower radially outwardly against the internal corrector cam surfaces, in a manner disclosed hereinabove in connection with Fig. 2. The particular cam follower nib 56 in position against its associated cam, controls the radial position of corrector trolley 42, in turn effecting the proper quadrantal error corrections on indicator 28 corresponding to the frequency band operated on.

The selective operation of the corrector system is performed by manually setting member 55. Fig. 10 is an enlarged cross-sectional detail through the cam selector mechanism. The upper cam follower projection 56 is engaged with internal cammed surface 80 of upper cam 60. Follower member 55 is in fixed mechanical relation with respect to trolley 42, through pin 81 extending from trolley arm 45 into a hole in the base of member 55. The other nibs 56, being 90° apart with respect to the engaged nib, do not interfere with the free and normal operation of the engaged cam.

Fig. 11 shows the coaction of projecting nib 56 of follower member 55 with cammed surface 80 of cam 60. The varying radial contour of internal cammed surface 80 controls the radial position of the trolley arms. Partial sectional view, Fig. 12, shows pin 81 extending from one of the trolley arms, 45, for engagement with settable cam follower member 55. The openings 82 in the base of member 55 correspond to the individual nibs 56 thereof, being selectively engageable with pin 81.

The selective engagement of pin 81 with the respective openings 82 in the bottom of follower member 55 to effect selective cam operation, is performed manually by lifting member 55 away from pin 81 against the action of the internal spring 83 and then angularly rotating member 55 until a nib 56 is engaged with the desired one of the cams 57, 58, 59, 60. A scale may be marked for visually ascertaining which cam and nib is engaged. When the upwardly displacing force on member 55 is released, spring 83 snaps it into position over pin 81, fixedly holding member 55 with respect to trolley 42. Internal spring 83 is normally under compression coaxially about rod 84, the bottom end 85 of which is threaded into trolley arm 44. The upper end of spring 83 is concentric within knurled thumb screw 86 and operable into the top threaded opening of member 55. A collar 87 on rod 84 engages the upper end of spring 83.

Selective engagement of the cams is accordingly readily effected simply by pulling cam follower member 55 away from pin 81; turning the member until the proper cam follower nib 56 engages its associated cam; and then releasing

member 55 to snap over pin 81. Dust cover 32 of the corrector mechanism is first opened to perform the selection and then closed over and locked with thumb nut 33.

5 A modified multiple quadrantal error corrector system is illustrated in Figs. 6 and 7. The quadrantal trolley 42 and associated mechanical connections to the loop antenna and indicator of this embodiment are similar to that previously described. A plurality of individual cams 91, 92, 93 and 94 are spaced one above the other by annular spacing rings 90, and are held together by the reduced diameter sections 95, 95 of shafts 96, 96. Flat-heads 97, 97 are on the tops of sections 95, 95. Shafts 96, 96 are slidably supported in elbows 98, 98 projecting from frame 99. A compression spring 100 is concentric about the lower end of each shaft 96, being between the lowermost supporting elbow and an intermediate collar 101 on the shaft.

10 The cam assembly 91 to 94 accordingly is normally biased upwardly against two normally stationary cams 102, 102. Cams 102, 102 are arranged on rod 103 which is supported in frame 99 across the top of the assembly, and have individual coaction with flat-heads 97, 97. Rod 103 extends through housing 27. A selector handle 104 is secured to the projecting end of cam rod 103. The angular position of cams 102, 102 is altered through the rotation of handle 104. When four cams are used, such as 91 to 94 illustrated, there are four corresponding positions for handle 104.

15 Fig. 15 is an end view of the selector handle 104 and associated escutcheon plate 105 secured on the adjacent side wall of housing 27 by screws 106. The four positions, Nos. 1, 2, 3 and 4, marked on plate 105 correspond respectively to the operative engagement of respective cams 91, 92, 93 and 94 with cam follower 110 extending from trolley 42. To insure rigid and stable positioning of cams 102, 102 after their being set, holes 107 are provided in escutcheon plate 105 opposite the setting positions, for engaging pin 108 which is spring biased towards plate 105. A knurled knob 109 is at the outer end of pin 108 for proper manipulation.

20 Fig. 14 is a cross-sectional detail illustrating the coaction of a selector cam 102 with cam assembly 91 to 94. Cams 102 and selector handle 104 of Figs. 6, 7, 14 and 15 are in position No. 4, corresponding to the engagement of corrector cam 94 with cam follower 110. Springs 100, 100 press the cam assembly against cams 102, 102, which, in position No. 4, cause accurate engagement of the cam 94 with cam follower 110. Upon due cam positioning, the selector cams 102, 102 and the cam assembly remain stationary, the operation of the quadrantal error corrector on the bearing indicator of the system then corresponding to the action of a single cam, namely the selected one. The remaining cams stay out of coaction with the cam follower 110 and trolley 42.

25 When selector cams 102, 102 are rotated to a new position, they press the cam assembly 91 to 94 against the continuous spring action of compression springs 100, 100, to accurately select another cam for coaction with cam follower 110. The dotted selector cam position 102' of Fig. 14 corresponds to position No. 1, the selection of cam 91 for coaction with the cam follower. The dotted positions of the cam assembly 91', 92', 93', 94', correspond to their lowermost position in the mechanism. The intermediate positions, Nos. 2

and 3, are selected similarly. It is unnecessary to open housing lid 32 to effect the corrector cam selection, since only external handle 104 need be operated to perform this.

To provide for non-interfering action in the selective movement of cam follower 110 between the respective cams 91 to 94, coating edge 111 of cam follower 110 is designed as shown in Fig. 16. The active surface of follower 110 is curved, and sufficiently wide to slide among the successive adjacent cams without disengaging at any point.

A further multiple quadrantal error corrector mechanism in accordance with the invention is illustrated in Figs. 8 and 9. Four cam sections are shown for selective coaction with cam follower 115 mounted at the joining of trolley arms 44, 45. The respective cams are in the form of split half sections pivoted upon post 116. Post 116 is bolted onto sub-frame 76 by bolt 117. The cam sections are spaced from each other by washers 118. Corrector cam units 121, 122, 123, 124 constitute the multiple corrector cam assembly for selective engagement with cam follower 115. The individual corrector cam units comprise two 180° sections of the previously described 360° internal cams. The cam units are individually mounted on semi-circular supports 121', 122', 123', 124' by screws 125. Their effective cammed surfaces project radially inwardly from the associated semi-circular support members, insuring proper contact of the cams with cam follower 115.

Toggle links 126 are attached to the free ends of the cam sections, being pivoted on ears 127 thereof. Each pair of links 126, 126 of a cam set is pivoted in a yoke 128 secured to an individual selector bar 130. Selector bars 130 extend through corresponding slots 132 (see Fig. 18) in housing 27, terminating in integral transverse handles 131. A compression spring 133 is arranged about each bar 130, positioned between housing 27 and yoke 128. Yokes 128 and toggle links 126 are thus normally biased inwardly, whereby the cam units are normally in the inoperative position when their selector bar 130 is in the inner position.

To select a cam unit for active coaction with follower 115, the corresponding selector bar 130 is pulled outwardly through its handle 131. Upper selector bar 130 attached to upper cam unit 121 is shown in the extended position, the cam thus being in operative or active relation with follower 115. To hold selector bar 130 in this outer position, against the retracting action of its spring 133, it is twisted 90° into a vertical position. Recessed portion 134 of bar 130 is in this manner permitted to lock transversely against narrow horizontal slot 132 in housing 27.

Figs. 17, 18 and 19 are enlarged detail sectional views more clearly illustrating the correlation of the respective selector parts of this construction. Selector bars 130 are rotatably joined to their respective yokes 128 by an expanded head 135 within the yokes. With the upper selected bar 130 maintained in the extended position, the corresponding cam unit 121 is engaged, a continuous 360° cam surface thereupon being effective on cam follower 115. The remaining three disengaged cams (122, 123, 124) are pivoted apart to their normally inoperative relation, forming a discontinuous arrangement wholly outside of contacting relationship with cam follower 115.

To change from one cam engagement to another in this arrangement, it is unnecessary to

open housing lid 32. The selected cam (corresponding to position No. 1), is first disengaged by rotating the vertically projecting handle 131 by 90°, then pressing it inwardly or releasing it to permit its spring 133 to force it back to the neutral or inoperative position. The cam thereupon spreads apart to the inoperative position. The selector bar (130) of the next desired cam is then pulled outwardly against its spring, to engage the cam with the cam follower, in the manner previously described in connection with cam unit 121.

A supporting and guiding member 140 is provided for each half of the cam assembly. Members 140 contain horizontal projecting shelves 141, 142, 143, 144 for the respective cam units 121, 122, 123, 124. A mounting flange 145 extends at the bottom of members 140 for their securing to sub-panel 76 by screws 146. The unpivoted or free ends of the semi-circular supports 121', 122', 123', 124', contain lugs 141', 142', 143', 144' which project onto the shelves 141, 142, 143, 144. The lugs engage the shelves through pins 147 passing therethrough and terminating in shoulders or larger heads 148 which ride in corresponding slots in the shelves.

The cam supports 121', 122', 123', 124' are accordingly horizontally supported between pivotal post 116 and the respective members 140, 140. Also, the horizontal pivotal movements of the cam supports are guided by the shelves 141, 142, 143, 144 of member 140. In this manner, the semi-circular cam units 121, 122, 123, 124 need not be very strong structurally, but merely of sufficient strength to coact with cam follower 115. The cam supports 121', 122', 123', 124' in coaction with the supporting and guiding members 140, 140 provide the necessary structural strength for the cam assembly while permitting free selective coaction of the respective cams.

Although preferred embodiments of the invention are herein disclosed using four cams in the multiple cam assembly, different numbers of cams may be used. As will be apparent to those skilled in the art, modifications and variations in the constructional features and arrangements illustrated may well be made, without departing from the broader spirit and scope of the invention as defined in the following claims.

What is claimed is:

1. A quadrantal error corrector for an indicator comprising: a plurality of corrector cams with individual pre-shaped cam surfaces; means mounting said cams one next to another; a cam follower coupled between the indicator and said cams, a member adjustably mounted on said cam follower, said member having a plurality of projections spaced in correspondence with the positions of said cams; and means for holding said member in its adjusted positions on said cam follower for selectively operating said projections against a corresponding cam surface, whereby selective quadrantal error compensation is effected on said indicator by the corrector.

2. A quadrantal error corrector comprising: a plurality of corrector cams; means spacedly mounting said cams one next to another; a cam follower member having a plurality of projections spaced in correspondence with the spacing of said cams; a follower-arm unit carrying said member at a free end thereof in coaction with said cam surfaces; and mechanism for selectively operating said projections against their corresponding cam surfaces including a spring me-

chanically biasing said member against said follower-arm unit, and an instrumentality for locking said member in the position on said unit whereby solely the selected projection engages with its corresponding cam surface.

3. A quadrantial error corrector for a direction finder comprising: a frame; a plurality of flat corrector cams with individual cam surfaces pre-shaped in accordance with respective radio frequency reception bands; means fixedly mounting said cams one next to another; a cam follower spring pressed toward said cams and coupled to an indicator, a member adjustably mounted on said cam follower and having a plurality of nibs projecting at different angular positions that are spaced corresponding to the spacing of said cams; and mechanism for holding said member in its adjusted positions on said cam follower for operating one of said nibs at a time against its corresponding cam surface, whereby selective quadrantial error compensation is effected on the indicator by the corrector.

4. A quadrantial error corrector for an indicator comprising: a plurality of corrector cams with individual internal cam surfaces pre-shaped in accordance with respective radio frequency reception bands; means spacedly mounting said cams one next to another; a cam follower member having a plurality of elements on the exterior surface thereof spaced in correspondence with the spacing of said cams and oriented in respectively different directions; a follower-arm unit arranged within said cams and adjustably carrying said member for selective coaction with said cam surfaces, said unit being coupled to the indicator; and mechanism for holding said member in its adjusted positions on said unit for selectively operating said elements against the corresponding cam surface to effect selective quadrantial error compensation on the indicator.

5. A quadrantial error corrector comprising: a plurality of corrector cams with individual internal pre-shaped cam surfaces; means fixedly mounting said cams one next to another; a cam follower member having a plurality of nibs on the exterior surface thereof, spaced in correspondence with the arrangement of said cams and oriented in respectively different directions; a spring-pressed follower-arm unit carrying said member in coaction with said cam surfaces; and mechanism for selectively operating said nibs against the corresponding cam surface including a spring mechanically biasing said member against said follower-arm unit, and an instrumentality for locking said member in position on said unit whereby solely the selected nib engages with its corresponding cam surface.

6. A quadrantial error corrector comprising: a plurality of corrector cams with individual cam surfaces pre-shaped in accordance with respective radio frequency reception bands; means spacedly mounting said cams one next to another; a tubular member having a plurality of elements on the exterior surface thereof, spaced in correspondence with the arrangement of said cams and oriented in respectively different directions; a spring-pressed leverage system carrying said member in coaction with said cam surfaces; and means for selectively operating said elements against the corresponding cam surface including a post secured to said leverage system, said member being rotatably mounted on said post, a spring mechanically biasing said member against said leverage system, and an instrumentality for locking said member in position on said

leverage system whereby solely the selected element engages with its corresponding cam surface.

7. A quadrantial error corrector comprising: a plurality of corrector cams with individual pre-shaped cam surfaces; means fixedly mounting said cams one next to another; a tubular member having a plurality of nibs spaced in correspondence with the arrangement of said cams;

10 a spring-pressed trolley arrangement for connection between a directional antenna and indicator carrying said member at a free end thereof in coaction with said cam surfaces; and means for selectively operating said nibs against the corresponding cam surface including a post secured to said trolley arrangement and extending transversely of the mounted cams, said member being rotatably mounted on said post, a compression spring within said member and about 15 said post for mechanically biasing said member against said trolley arrangement, and an instrumentality for locking said member in position on said trolley whereby solely the selected nib engages with its corresponding cam surface.

25 8. A quadrantial error corrector comprising: a plurality of corrector cams with individual cam surfaces pre-shaped in accordance with respective radio frequency reception bands; means spacedly mounting said cams one next to an-

other; a tubular member having a plurality of projections on the exterior surface thereof, spaced in correspondence with the spacing of said cams and oriented in respectively different directions; a spring-pressed follower-arm unit

35 carrying said member in coaction with said cam surfaces; and mechanism for selectively operating said projections against a corresponding cam surface including a post secured to said follower-arm unit, said member being rotatably mounted on said post, a compression spring mechanically biasing said member against said follower-arm unit, and an instrumentality for locking said member in position on said unit whereby solely the selected projection engages with its

45 corresponding cam surface; and a knob extending from said member, concentrically about said post, for manually controlling the member locking by said instrumentality.

9. A quadrantial error corrector comprising: a plurality of corrector cams with individual internal pre-shaped cam surfaces pre-shaped in accordance with respective radio frequency reception bands; means spacedly mounting said cams one next to another; a tubular member

55 having a plurality of nibs on the exterior surface thereof, spaced in correspondence with the spacing of said cams and oriented in respectively different directions; a follower-arm unit arranged within said cams and carrying said member in

60 coaction with said cam surfaces; and mechanism for selectively operating said nibs against a corresponding cam surface including a post secured to said follower-arm unit and extending transversely of the mounted cams, said member being

65 rotatably mounted on said post, a spring mechanically biasing said member against said follower-arm unit, and an instrumentality for locking said member in position on said unit whereby solely the selected nib engages with its corresponding cam surface; and a knob extending above said member, concentrically about said post, for manually controlling the member locking by said instrumentality.
